UNITED STATES PATENT OFFICE

JOHN H. WIGGINS, OF BARTLESVILLE, OKLAHOMA

METHOD OF BUILDING ROOFS FOR LIQUID-STORAGE TANKS AND GAS HOLDERS

Application filed July 5, 1927. Serial No. 203,589.

This invention relates to liquid storage tanks and gas holders of the type described in my Patent 1,645,813 dated Oct. 11, 1927, in which the top or roof of the tank is constructed of members, usually metal plates, 5 that are connected to each other and to the side wall of the tank in such a way as to produce a downwardly concave-shaped, gas-tight roof that is capable of flexing upwardly and assuming an upwardly concave-shape 10 under certain conditions, thus increasing the volume of the vapor space in the upper portion of the tank. One method that can be used to construct such a tank roof is to connect the roof plates to each other and to the side wall of the tank when said plates are resting upon a downwardly concave-shaped 15 supporting structure that sustains the roof when it is in its normal, depressed position, but one disadvantage of such a method is that the roof plates wrinkle abnormally when the roof reaches a horizontal position in 20 passing from its depressed position into its raised position, or vice versa.

25 The object of my present invention is to provide a method of constructing a tank roof of the kind referred to, that eliminates wrinkling or reduces wrinkling of the roof plates when the roof is passing from its normal, depressed position into its raised 30 or inverted position, or vice versa, without, however, weakening the roof or causing the plates or the joints of the roof to be subjected to abnormal strains when 35 the roof is in its raised position. To this end I propose to connect the roof plates to each other and to the side wall of the tank while said plates are sustained in a substantially horizontal position at a point above 40 the depressed or normal position of the roof, and thereafter permit the central portion of the roof to deflect sufficiently to put the plates and the joints of the roof under some tension, and finally come to rest in its normal 45 position on a downwardly concave-shaped supporting structure. Preferably, the structure that is used to support the roof in its normal position is used to support the roof plates while they are being fastened together 50 and attached to the side wall of the tank, and

at the completion of said operation the central portion of said supporting structure is depressed sufficiently to produce a downwardly concave-shaped support for the roof. In constructing a roof that has only a relatively slight movement upwardly and downwardly from a horizontal plane intermediate the normal and inverted positions of the roof, the supporting structure on which the roof plates are sustained during the operation of connecting them together is arranged substantially horizontal in close proximity to said horizontal plane, but in constructing a roof that has a relatively great movement upwardly and downwardly from said intermediate horizontal plane, the supporting structure on which the roof plates are sustained while they are being connected together is arranged so that it will be inclined downwardly slightly for example, with a 60 drop of, say, one foot at the center of the structure, and after the roof plates have been connected together and attached to the side wall of the tank, the central portion of said supporting structure is dropped another foot. 65 Accordingly, when the roof is in its normal depressed position the central portion of the roof will be two feet below the horizontal plane at the top edge of side wall of the tank, and when the roof flexes upwardly into its inverted or elevated position, the central portion of the roof will be two feet above said horizontal plane. By constructing the roof in this manner I utilize the tension of the roof plates solely or in conjunction with some 70 extra metal that is built into the roof due to fastening the roof plates together while they are sustained on a slightly dished support, to permit the roof to flex upwardly into its upwardly concave-shape without liability 75 of straining the roof, and as there is only a small amount of excess metal in the roof, the roof plates will not wrinkle abnormally while the roof is passing through the intermediate horizontal plane in moving from its 80 depressed to its elevated position, or vice versa.

Figure 1 of the drawings is a vertical transverse sectional view, illustrating my improved method of constructing the top or roof of a 100

liquid storage tank or gas holder, showing the supporting structure for the roof plates in the position it occupies when the roof plates are being connected together and attached to the side wall of the tank; and

5 Figure 2 is a vertical transverse sectional view, showing the central portion of said structure dropped at the completion of the operation of connecting the roof plates together, so as to serve as a support for the 10 roof when it is in its normal depressed position.

Referring to the drawings, A designates the side wall of a liquid storage tank that is 15 equipped with a roof or top B that is of downwardly concave-shape when it is in its normal or depressed position, and which is capable of flexing upwardly into an upwardly concave shape so as to increase the volume of 20 the vapor space above the surface of the liquid in the tank. Said roof is preferably constructed from metal plates that are joined together and attached to the side wall of the tank in such a way as to form a gas-tight 25 closure for the tank, and a relief valve is mounted on the roof so as to relieve or reduce the internal pressure of the tank when the roof approaches its extreme elevated position or inverted position, as described in my pending 30 application previously referred to.

In building the roof I prefer to attach the roof plates to each other and to the side wall of the tank while said plates are sustained on a supporting structure, designated as an entirety by the reference character C, that is 35 arranged inside of the tank in a substantially horizontal position in close proximity to a horizontal plane at the top edge of the side wall of the tank, as shown in Figure 1. Said 40 supporting structure is herein illustrated as being sustained by brackets or lateral projections 1 on the side wall of the tank, and by vertically-disposed uprights formed by posts 3 of different lengths which are in turn mounted 45 on removable supports 4 of different lengths that rest upon the bottom of the tank, the posts 3 gradually decreasing in length or height from the side wall of the tank towards the center of the tank and the removable 50 supports 4 increasing gradually in height from the side wall of the tank towards the center.

At the completion of the operation of joining the roof plates together and attaching them to the side wall of the tank, the supports 4 at the lower end of the posts 3 are removed so as to permit the posts 3 to rest directly upon the bottom of the tank, thus causing the central portion of the supporting structure C to 55 drop downwardly as shown in Figure 2, and assume the shape of a downwardly concaved support on which the roof rests when it is in its normal depressed position.

The position in which the supporting structure C is arranged during the operation of

connecting the roof plates together may be varied and the distance that the central portion of said supporting structure is thereafter dropped may be varied. It is not desirable to drop the central portion of the supporting 70 structure a distance equal to the maximum deflection of the roof if the roof was sustained solely by the side wall of the tank, as this might result in straining the joints between the roof plates and between the peripheral edge of the roof and the side wall of the tank. 75 Various other means than the posts 3 and removable supports 4 can be used to sustain the supporting structure C, and if desired, the removable supports 4 can be arranged between the upper ends of said posts and the supporting structure C, instead of between the lower ends of said posts and the bottom of the tank.

Having thus described my invention, what 85 I claim as new and desire to secure by Letters Patent is:

1. A method of constructing a tank roof that is attached at its peripheral edge to the side wall of the tank, and which is capable 90 of flexing upwardly and downwardly from a horizontal plane intermediate the two extreme positions of the roof, consisting in connecting the roof members to each other and attaching them to the side wall of the tank 95 while said roof members are arranged at a point above the normal depressed position of the roof, and at the completion of said operation permitting the roof to assume a downwardly concave-shape.

2. A method of constructing a tank roof that is attached at its peripheral edge to the side wall of the tank, and which is capable 100 of flexing upwardly and downwardly from a horizontal plane intermediate the two extreme positions of the roof, consisting in connecting the roof members to each other and attaching them to the side wall of the tank 105 while said roof members are arranged at a point above the normal depressed position of the roof, and at the completion of said operation permitting the central portion of the roof to deflect a distance less than the maximum deflection of the roof if it were supported solely by the side wall of the tank. 110

3. A method of constructing a tank roof that is attached at its peripheral edge to the side wall of the tank, and which is capable of 115 flexing upwardly and downwardly from a horizontal plane intermediate the two extreme positions of the roof, consisting in connecting the roof members to each other and attaching them to the side wall of the tank by gas-tight joints while said roof members are sustained by a supporting structure that is 120 arranged substantially horizontal or with its central portion located at a point above the normal depressed position of the roof, and thereafter lowering the central portion of 125 said supporting structure so as to cause it to 130

assume the shape of a downwardly-concaved support on which the roof rests when it is in its normal, depressed position.

4. A method of constructing a tank roof that is attached at its peripheral edge to the side wall of the tank, and which is capable of flexing upwardly and downwardly from a horizontal plane intermediate the two extreme positions of the roof, consisting in arranging a substantially horizontally-disposed supporting structure inside of the tank, adjacent the upper edge of same, on uprights, mounting metal plates on said structure and connecting said plates to each other and to the side wall of the tank, and thereafter changing the length of said uprights in such a way as to cause the supporting structure and the roof thereon to assume a downwardly concave-shape.
5. A method of constructing a tank roof which is adapted to flex upwardly and downwardly above an intermediate horizontal plane, consisting in joining metal plates together and attaching them to the side wall of the tank so as to form a gas-tight roof, sustaining the plates during the above described operation by a supporting structure inside of the tank, and subsequently changing the shape of said structure so as to cause the central portion of the roof to deflect sufficiently to put some tension on the plates and joints of the roof and thereafter come to rest in its normal downwardly deflected condition on said structure.
6. A method of constructing a tank roof that is adapted to flex upwardly and downwardly from an intermediate horizontal plane when the tank is in normal use, consisting in joining metal plates together and attaching them to the side wall of the tank so as to form a tight top for the tank, sustaining the plates during the above operation by a supporting structure which is of different shape than the roof when said roof is in either of its extreme positions, and at the completion of said operation converting said supporting structure into a downwardly concaved support on which the roof rests when it is in its normal, downwardly-deflected condition.

JOHN H. WIGGINS.
